Filed May 27, 1968, Ser. No. 12,094

Term of patent 14 years

Int. Cl. D23—04

U.S. Cl. D23—146

FIG. 1.

FIG. 4.

FIG. 5.

FIG. 6.

FIG. 3.

FIG. 1 is a perspective view of a dehumidifier embodying my new design;

FIG. 2 is a front elevational view thereof;

FIG. 3 is a right side elevational view thereof;

FIG. 4 is a top plan view thereof;

FIG. 5 is a rear elevational view thereof; and

FIG. 6 is a fragmentary vertical section corresponding to one taken on the line VI—VI of FIG. 2.

The bottom face of the dehumidifier is hidden from view in normal use.

The dominant feature of my design resides in the portions shown in full lines.

I claim:

The ornamental design for a dehumidifier, substantially as shown and described.
